UNITED STATES PATENT OFFICE.

OSCAR A. ROHRER AND BRUCK REINBACH, OF WAVERLY, ILLINOIS.

BLADE-SHARPENER.

1,115,025.

Specification of Letters Patent.

Patented Oct. 27, 1914.

Application filed December 20, 1913. Serial No. 807,980.

To all whom it may concern.

Be it known that we, OSCAR A. ROHRER and BRUCK REINBACH, citizens of the United States, residing at Waverly, in the county 5 of Morgan, State of Illinois, have invented a new and useful Blade-Sharpener, of which the following is a specification.

This invention relates to a sharpener for blades and more particularly to a device 10 which will hold the sharpening blade in proper position so that it will bear against and sharpen various implements such as the cutting knives of a lawn mower and so forth.

A further object is to provide a triangular sharpening member with the three faces thereof ribbed similar to a file and to provide a handle formed of wire which will resiliently engage the triangular sharpening member and hold the same with the sharpening faces thereof at the required angle. 20

A further object is to provide a sharpening device in which the triangular shaped sharpening blade is held at adjusted angles with the handle which engages the same 25 forming a guide so that the knife blade of the lawn mower or allied tool will be sharpened, the cutting face thereof being sharpened at the proper and predetermined angle.

A further object is to provide a blade 30 sharpener in which the handle will project beyond the sharpening member and form a guide holding the sharpening member at a certain and predetermined angle to the blade whereby the cutting edge of the blade will 35 be sharpened and maintained at the proper angle to the blade.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 45 within the scope of what is claimed, without departing from the spirit of the invention.

In the drawings accompanying this specification and forming a part thereof, the

preferable embodiment of our invention is 50 illustrated, in which:

Figure 1 is a view in perspective of our improved blade sharpener. Fig. 2 is a side view thereof. Fig. 3 is a view of the device with a slightly different form of locking member. Fig. 4 is a side view of the modified form. Fig. 5 is a view in perspective of a somewhat modified form of the locking member illustrated in Fig. 1. Fig. 6 is a view in perspective of a somewhat modified 60 form of the locking member illustrated in Fig. 3.

Referring to the drawings in which similar reference numerals designate corresponding parts throughout the several views, 4 65 is a triangular-shaped sharpening member which is provided with the abrasive faces 5 which are adapted to contact with and sharpen blades of various cutting articles.

The triangular sharpening member may 70 be made from the body portion of an ordinary triangular file should it be so desired. In order to hold the sharpening member in proper position, a handle is provided and is formed with the U-shaped body portion 6, 75 from which project the angularly disposed arms 7 which are bent sharply upward at their ends as at 8, between which extends the holding bar 9. The arms 7, upwardly extending ends 8 and bar 9 rest against the 80 two sides of the sharpening member and hold the same with the outlying sharpening face substantially perpendicular to the plane of the body portion 6, the same being clearly illustrated in Fig. 2 of the drawings. In 85 order to rigidly hold the sharpening member so positioned, the locking member 10 is provided and which is formed with the transversely extending end bar 11 and from which extend the projections 12 and which 90 are connected to the arms 13. The arms 13 rest against the side wall of the sharpening member and project below the U-shaped body portion 6. The arms then cross beneath the U-shaped body portion as at 14 95 and from which project the legs 15, which intertwine or bend around the sides of the U-shaped body portion 6. Thus the legs 15

and cross bars 14 will coat with the sides of the body portion 6 and hold the arms 13 and 7 in forced contact with the sides of the sharpening member so that it will be held rigidly in place. The portions 12 and 8 in conjunction with the end bars 9 and 11 constitute a guide for a blade 16 so that as the sharpener is moved longitudinally of the blade with the end bars 9 and 11 in contact therewith, the edge formed or sharpened upon the blade will be at a predetermined and desired angle for the proper operation of the blade. The angle at which the cutting edge forms, depends upon the use to which the blade is to be put and by the handle herein disclosed, the said angle may be varied by bending the portions 12 toward and away from the sharpening face 5 of the sharpening member.

20 A somewhat modified form of locking member 17 is illustrated in Figs. 3 and 4 and is formed with the cross bars 18 and intertwining legs 19. The arms which project from the cross bars 18 and which are indicated at 20 extend along the face of the sharpening member for a limited distance only and are connected by a cross bar 21. Thus the bar 21 will force the sharpening member up within the crotch or notch defined by the arms 7 and portions 8 of the handle, thus holding the sharpening member rigidly in place. This construction as illustrated in Fig. 4 allows the sharpening device to be used with a blade 22 of some considerable width and also allows the blade to be sharpened at any desired angle or to sharpen a blade in which the angularity or obliquity of the cutting edge may vary throughout the blade. The cross bar 9 will 30 act in the capacity of a ledge or shoulder preventing the blade from slipping laterally across the abrasive face 5 of the sharpening member. Thus should one of the faces of the abrasive member become dulled the legs 35 of the locking member may be entwined or engaged from the sides of the U-shaped body portion 6 which would allow the locking member to become released from the handle, thus releasing the sharpening member. The sharpening member may then be turned so as to present another of its abrasive faces. The entire device may be easily and cheaply constructed, and is formed of resilient wire so that it may be easily assembled and as readily disassembled.

50 The somewhat modified forms of the locking members illustrated in Figs. 5 and 6 are similar to the locking members illustrated in Figs. 1 and 3, with the exception that the double cross bars 14 and 18 are omitted and the cross bars 14' and 18' substituted therefor. This makes a somewhat stronger and neater appearing structure should it be so desired.

Having thus fully described our invention, what we claim is:

1. A snap handle for a polygonal shaped sharpening member comprising a stationary member including a pair of connected spaced rods, the extremities of said rods being out of the plane of said rods and with the ends being bent sharply in a return direction, a locking member including a front and rear portion with a bar-like member extending laterally thereof at the point of division between the front and rear portion of said locking member, said bar-like member contacting with and pivoting upon the spaced rods of the stationary member, the rear portion of said locking member including legs adapted to resiliently entwine with the spaced rods of the stationary member, the front portion of said locking member adapted to contact with the said sharpening member and to force the same into interlocking relation with the sharply bent portion of the said stationary member.

2. A handle for a triangular shaped sharpening member including a stationary portion and a locking member, said stationary portion including a body portion of spaced rods secured together at their extremities, the extremities of said rods being bent laterally, and then sharply in a return direction for a limited distance, and a bar extending between the extremities thereof, said locking member including an end bar, sides connected thereto and extending therefrom, the said sides being bent to conform with the triangular faces of the sharpening member, said sides being bent to form cross members contacting with and extending between the spaced bars of the stationary member, the said cross or transverse members of the locking member being bent rearwardly and forming legs interlocking with the spaced bars of the stationary body portion, the transverse members and interlocking legs holding the said end bars and interlocking members in forced contact with the said triangular-shaped sharpening member and holding the same rigidly in position in the stationary body portion.

3. A handle for a sharpener of polygonal cross section including a stationary member, said stationary member including a front portion and a rear portion, the front portion being offset at an angle with respect to the rear portion, the said rear portion forming a finger engaging portion and the front portion adapted to bear against the sharpener, a locking member including a front portion adapted to bear against the sharpener to hold the same in rigid contact with the front portion of the stationary member, said locking member further including a portion detachably and rotatably engaging the portion between the front and

rear portions of the stationary member, and the said locking member further including means resiliently engaging the rear portion of the stationary member and holding the 5 front portion thereof into forced contact with the said sharpener.

In testimony that we claim the foregoing

as our own, we have hereto affixed our signatures in the presence of two witnesses.

OSCAR A. ROHRER.
BRUCK REINBACH.
